Richard B. Dyer, ATTORNEY.

UNITED STATES PATENT OFFICE.

BRUCE G. BOND, OF NEW YORK, N. Y.

SAXOPHONE VALVE.

Application filed July 19, 1927. Serial No. 206,999.

This invention relates to improvements in saxophone valves and has as its general object to provide a valve which will be substantially unaffected by the accumulation of moisture and which will therefore be proof against leaking, the valve being so constructed that it will at all times remain in a dry state and maintain its original contour, thus insuring a perfect fitting of the valve to its opening, in the operation of the valve.

Another object of the invention is to provide, in a saxophone valve, novel means for effecting ventilation of the pad of the valve so as to prevent the accumulation or condensation of moisture in the pad.

Another object of the invention is to provide, in a saxophone valve, a pad of novel construction, and to so mount the pad as to provide for ventilation thereof.

Another object of the invention is to provide, in a saxophone valve, a pad which will embody means, cooperating with the cup of the valve, for effectually preventing displacement of the pad and at the same time permit of ready removal of the pad and the substitution of a new pad or the repair of the pad removed.

While the accompanying drawings and the description which is to follow, constitute a disclosure of the preferred embodiment of the invention, it will be understood that various changes may be made within the scope of what is claimed.

In the accompanying drawing:

Figure 1 is a side elevation of a saxophone valve embodying the invention.

Figure 2 is a horizontal sectional view taken substantially on the line 2—2 of Figure 1 looking in the direction indicated by the arrows,

Figure 3 is a diametric sectional view taken substantially on the line 3—3 of Fig. 2 looking in the direction indicated by the arrows,

Figure 4 is a view partly in side elevation and partly in section illustrating the pad of the valve removed from the key, and likewise illustrating a device which may be employed for removing and replacing the pad,

Figure 5 is a detail horizontal sectional view taken substantially on the line 5—5 of Fig. 4 looking in the direction indicated by the arrows,

Figure 6 is a fragmentary bottom-plan view of a portion of the pad.

In the drawings the pad cup of the key is indicated in general by the numeral 1, and the pad is indicated in general by the numeral 2. The pad cup 1 comprises the usual circular body portion 3 and depending, annular, circumscribing flange 4 which projects from the under side of the body portion 3 and within which the pad 2 is seated.

The pad 2 comprises a disk 5 which is preferably of circular contour and of some metal, such as aluminum, which will be proof against rusting, and this disk is formed with a plurality of openings indicated by the numeral 6. These openings provide for passage of air to the body of the pad, in a manner which will presently be explained. As shown in Figure 2 of the drawings, the openings 6 are arranged in two or more annular series concentric to one another and the openings are preferably staggered so as to provide for a uniform circulation of air which passes through these openings. The pad 2 further comprises a filler 7 which preferably consists of a number of super-imposed disks 8 of felt or other soft and pliable material which is likewise capable of absorbing moisture and which is also of a character to insure of quick drying of any moisture, or any accumulating thereon. These disks are arranged in marginal registration, and the pad is completed by a covering 9 which is applied over the surface of the lowermost disk 8 of the filler and marginally disposed snugly about the registering peripheries of the disks, the covering 9 being of such diameter, in blank form, that the marginal portion thereof may be directed inwardly and disposed flat, as indicated by the numeral 10, against the upper side of the uppermost disk 8 and against the under side of the disk 5 at the periphery of the latter, the overturned marginal portion 10 of the covering 9 being united to the under side of the said disk 5 in any suitable manner as, for example, by the use of a suitable adhesive. The covering 9 of the pad is preferably of kid, and preferably the covering is securely held assembled with the filler disk assemblage 7 through the medium of stitches 11 which are passed through the lower side of the cover 9 and through the overturned marginal portion 10 of said cover, the stitches passing, of course, through the marginal portions of the assembled disks 8.

The pad 2 may be held within the open under side of the key pad cup 1 in any suitable manner as, for example, by forming the inner side or surface of the flange 4 with 5 screw threads 12 which may be of such cross-sectional contour as to admit of the pad being threaded into the said underside of the pad cup 1 and retained in place by the automatic conformation of the rim portion 10 of the cover 9 to the shape of the screw threads as shown in Fig. 3 of the drawings, it being understood, however, that any means may be employed for holding the pad in place, so long as the means will permit of removal of the pad. 15

In order that the pad may be suitably ventilated so as to provide for quick evaporation of any moisture that might be temporarily deposited upon the pad, the flange 4 20 of the pad cup 1 of the valve is formed, preferably, at diametrically opposite points, with slots 13 which extend circumferentially of the flange for a greater or less distance and provide narrow air passages through 25 which air may enter the pad cup 1 between the portion 3 thereof and the upper side of the disk 5, the pad being so arranged within the flange 4 as to be supported with the disk 5 in somewhat spaced relation to the body 30 portion 3 of the pad cup. It will be apparent at this point that the overturned marginal portion 10 of the cover 9 extends only a short distance inwardly from the periphery of the uppermost disk 8 of the filler 7 35 and terminates, in fact, at the outer sides of the outer series of openings 6, so that the uppermost disk 8 is spaced below the disk 5 thus providing an air space between said disk 8 and said disk 5 and thus permitting 40 the free circulation of air in the space by way of the openings 6.

From the foregoing it will be evident that the invention contemplates a valve for saxophones of such construction that the pad 45 thereof will be at all times ventilated thus maintaining the pad in a dry condition and providing for rapid evaporation of any moisture which might temporarily condense upon the surface of the pad. Therefore, the 50 pad will maintain its original contour and condition and consequently will at all times effectually co-act with the seating surface above the opening in respect to which the valve is mounted, thus overcoming the disadvantages which are presented by pads and valves as ordinarily constructed. 55

In order that the pad embodying the invention may be removed from the pad cup and replaced, the disk 5 is formed in its periphery with a notch 14, and the location of 60 this notch is preferably indicated by a small spot 15 of ink or other coloring matter which is impressed upon the upper surface of the cover 9 of the pad at a point directly 65 opposite the notch and therefore very close

to the periphery of the pad. The means which is preferably employed to remove the pad from the valve, comprises a handle 16 which is provided at one end with a stud 17 which is of such dimensions and contour to adapt it to be fitted at its extremity into the notch 14, the peripheral portion of the pad 2 being slightly deflected by engaging the stud 17 there-against and moving the stud inwardly so as to permit of depression of this portion of the pad and engagement of the end of the stud in the notch 14, whereupon the device, as may be seen, may be employed substantially in the manner of a spanner wrench. 70

I claim:—

1. A key valve for wind musical instruments including a pad cup having an open side, and a pad supported within the open side of the cup in position to provide an air space between the inner side of the pad and the opposing side of the cup, the said cup having an air passage communicating with said space whereby to provide for the circulation of air within the space and over said 80 surface of the pad. 85

2. A valve for wind musical instruments including a pad cup having an open side, and a pad supported within the said side of the cup in spaced relation to the closed side 95 thereof, the pad cup having an air passage in communication with its interior to provide for the circulation of air therein over the inner surface of the pad. 100

3. A valve for wind musical instruments including a pad cup comprising a flat circular body portion having a peripheral flange, and a pad supported by the flange in spaced relation to the opposing side of the body portion to provide an air space between the said body portion and the opposing face of the pad, the flange having opposed air passages in communication with said space and providing for the circulation of air within 105 said space. 110

4. A valve for musical instruments including a pad cup having an open side, and a pad supported in the said side of the cup and comprising a perforated disk, and a pad body supported upon the outer face of the disk, the pad being supported with the disk in spaced relation to the inner wall of the pad cup whereby to provide an air space in the cup from which space air may pass through the perforation in the disk to the 120 pad body, the pad cup having an air passage in its side wall in communication with the said space to provide for the circulation of air within the space. 115

5. A valve for wind musical instruments 125 including a pad cup having an open side, and a pad comprising a disk, a filler, and a cover disposed about the filler and having an inturned marginal portion united to a face of the disk, the disk being provided with 130

- perforations, the said pad being arranged within the open side of the pad cup with the disk of the pad in spaced relation to the inner wall of the pad cup, the said pad cup 5 having an air passage in communication with the space between the disk and inner wall of the cup to provide for circulation of air within the pad cup and over the surface of the said disk.
- 10 6. A valve for wind musical instruments including a pad cup having an open side surrounded by a circumferential flange, the flange being provided interiorly with screw threads, and a pad threaded at its periphery 15 within the flange and supported thereby with its side which opposes the interior of the pad cup, in spaced relation thereto to provide an air space, the said pad cup having an air passage in communication with said 20 air space to provide for the circulation of air within the cup.
7. A valve for wind musical instruments including a pad cup having an inner wall and a circumferential wall providing an 25 open side, and a pad disposed within the open side of the pad cup, the said pad comprising a perforated disk, a filler, and a cover disposed over one face of the filler and about the periphery thereof and having 30 a marginal portion overturned against the other face of the filler and united to the disk, the disk being spaced with respect to the inner wall of the cup to provide an air space between said wall and the disk, the pad cup 35 being provided with an air passage in communication with said air space to provide for the circulation of air within the pad cup over the disk of the pad and through the perforations therein to the filler of the pad.
- 40 8. A valve for wind musical instruments including a pad cup having an open side flange, and a pad disposed within the said side of the pad cup and spaced from the inner wall of said cup to provide an air space, the said pad comprising a perforated 45 disk, a filler, and a cover disposed over one face of the filler and about the periphery thereof and having a marginal portion overturned against the other face of the filler and united to the disk, the pad cup being 50 provided with an air passage communicating with the air space to provide for the circulation of air within the pad cup and over the disk, the said disk being provided in its periphery with a notch for the engagement of a tool for effecting removal and replacement of the pad.
9. A valve for wind musical instruments including a pad cup having an open side, and a pad disposed within the open side of 55 the pad cup and spaced from the inner wall of said cup to provide an air space, the said pad comprising a perforated disk, a filler, and a cover disposed over one face of the filler and about the periphery thereof and having a marginal portion overturned 60 against the other face of the filler and united to the disk, the pad cup being provided with an air passage communicating with the air space to provide for the circulation of air therein and over the disk, and means secured through said cover and the filler and the overlapped marginal portion of the cover and uniting the cover and filler.
10. A valve for a wind musical instrument 65 embodying a cup and a pad, and means in the cup for ventilating the pad.

In testimony whereof I affix my signature.

BRUCE G. BOND.
